UNITED STATES PATENT OFFICE.

OTHNIEL GILMORE, OF EAST BRIDGEWATER, MASSACHUSETTS.

SOLE-LEVELING MACHINE.

SPECIFICATION forming part of Letters Patent No. 231,707, dated August 31, 1880.

Application filed June 4, 1880. (No model.)

To all whom it may concern:

Be it known that I, OTHNIEL GILMORE, of East Bridgewater, county of Plymouth, State of Massachusetts, have invented an Improvement in Sole-Leveling Machines, of which the following description, in connection with the accompanying drawings, is a specification.

This invention relates to mechanism for leveling the soles of boots and shoes, and is an improvement on that class of machines represented in United States Patent No. 44,946, heretofore granted to me, and on United States Patent No. 38,257 to B. Q. Budding, to which reference may be had.

15. In the said Budding machine the stroke of the leveling-roller was always equal to the length of the sole, and was produced by a crank-motion, which necessarily gave to the said roller a variable speed and caused it to 20 strike the ball of the sole with a blow, as it were, when the roll passed from the shank upon the ball, which, besides injuring the appearance of the sole, made it very difficult for the operator to control the roller; and, further, 25 in that machine, owing to the connection of the treadle mechanism with the front end of the frame upon which the roller traveled, the pressure of the leveling-roller was always less at the shank than at the ball and toe, where- 30 as the pressure should be uniform or in excess at the shank.

In my patented machine, to overcome these difficulties, I mounted the shoe upon a swiveling jack, but continued to use the crank to 35 move the leveling-rollers, shortening, however, its throw, which enabled me to cause the said roller to reciprocate uniformly over a portion of the sole less than its whole length, the change of position from time to time of the jack mech- 40 anism horizontally enabling me to bring under the roller a different part of the sole.

I have now devised a mechanism whereby I am enabled to impart to the leveling-roller reciprocations variable in their length accord- 45 ing to the will of the operator, and at the same time the pressure of the roller upon the sole is kept substantially uniform by means of a spring, yet during this reciprocation the degree of this pressure may be increased or de- 50 creased at will by means of a foot-treadle.

To so operate this leveling-roller I have combined with the arm carrying it a set of reversing-pulleys under control of the operator, who, by a suitable hand-lever, can shift the clutching mechanism so as to engage either one or the other of two oppositely-driven pulleys or surfaces, and make the direction and length of each stroke of the leveling-roller as may be desired.

In the two patented machines referred to, 60 to prevent the leveling-roller from dropping as it left and after it left the toe, which would spoil the sole at the toe, it was necessary to employ a toe piece or rest the top of which was substantially at the level of the sole at 65 the toe and extended beyond the said toe. In this present machine I have obviated the use of a toe-piece by pivoting upon the roller-carrying arm a lever-controller, which, as the roller passes from the toe end of the sole, is 70 thrown automatically into position to arrest the descent of the arm and roller, so that the latter cannot fall below the level of the toe end of the sole; but the lever-controller is so actuated automatically as the leveling-roller 75 arrives in position above the shank of the sole that the arm and roller are permitted to drop and follow the curvature of the shank even though its lowest face be lower than the toe end of the sole.

I prefer to use a rotating spider having two or more rigid radially-projecting metal lasts, and with it a locking device to retain each last with a shoe upon it locked in proper position with relation to the line of reciprocation of the leveling-roller; but it will be obvious that I might employ one single last properly mounted on the frame.

Figure 1 represents, in side elevation, partially in section, a leveling-machine containing 90 my improvements; Fig. 2, a top view thereof, the reversing or clutch mechanism being partially in section; and Fig. 3, a front-end view thereof.

The frame-work A of the machine will be 95 of any proper shape to support the working parts.

The spider B, connected with the shaft C, held in suitable bearings, has upon it two or more metal lasts, D. This shaft C has also a 100

notched disk, E, adapted to be engaged by a locking device, F, herein shown as a shaft or rod with two arms, one of which, the short one, (see Figs. 1 and 2,) engages a notch in the disk E, the other or longer arm, f^2 , made also as a handle, being connected with a spring, a , so that the said spider and lasts may be turned and brought into position as may be desired and be locked.

- 10 The main shaft b of the machine has splined upon it a double conical friction-hub, G, having preferably two leather-covered faces, 23, a central annular groove, 4, in the hub being entered by a pin, 5, of an arm, c , of a rock-shaft, H, it having an arm, c' , connected by link I with an arm, c^2 , of a short shaft or stud, c^3 , having connected with it a handle, c^4 , by which the operator can move the hub longitudinally in either direction on the said shaft 15 b and cause one or the other of its friction-faces to engage or enter the preferably conical faces of one or the other of the two constantly but reversely driven pulleys J K loose on the shaft b , thus positively rotating the said shaft 20 in one or the other direction so long as the hub and a pulley are kept in engagement. The pulleys J and K will be moved in the direction 25 of the arrows upon them.

The shaft b has fixed upon one end of it a pinion, b' , that engages and moves a larger toothed gear, b^2 , fast on a shaft, b^3 . This latter shaft, at or near its center, has a pinion, b^4 , (shown partially in Fig. 1 by breaking away the frame-work A,) and the said pinion is made 30 to engage a rack-bar, d , fixed to a carriage or plate, d^2 , having ears d^3 , which serve to hold the journals or pivots d^4 of the pivoted arm d^5 , the said pinion b^4 and rack-bar reciprocating the said carriage and its attached parts for a 35 greater or less distance, according to the time the operator holds the clutch mechanism in contact, and in one or the other direction, according to which one of the loose pulleys the 40 said hub engages. This arm carries a rod or shaft, e , upon which is secured, by the screw e^2 , the oscillating carrier M, in which is mounted 45 loosely the leveling-roller m^2 . This roller-carrier M has attached to it a handle, m^3 , to enable the operator to turn the carrier axially 50 upon or with the shaft e in the arm, to thus permit the roller to be held or pressed upon any desired part of the rounding surface of 55 the shank of the sole, or to follow correctly the curves between the shank and ball of the sole.

In some parts of the sole the strokes of the leveling-roller should be very short, and in others longer, and this may be done at the will of the operator by moving the hand-lever c^4 .

- 60 The arm d^5 has pivoted upon it the arm-controlling device f , herein shown as connected by spring f^2 with a fixed stud, f^3 , of the frame.

When the arm and carriage are drawn back so that the roller passes from the toe of the 65 sole the controller drops into the position

shown in dotted lines, Fig. 1, and acts as a foot to prevent the descent of the arm and roller so far as to pass below the level of the toe of the sole; but as the arm and carriage move forward, as in Fig. 1, the spring f^2 acts 70 to draw the controller back, as in full lines, and then the arm may descend to permit the roller to travel down along the shank of the sole.

Instead of the particular controller herein 75 shown and described, I may employ any other suitable and proper device to arrest the descent of the roller-arm when the roller passes off the toe of the sole.

The foot-treadle g has a rod, g' , upon which 80 is placed the cross-bar g^2 of the connecting-link g^3 , attached at its upper end with the collar g^4 on the stud g^5 , attached to the carrier M. A spring, g^6 , is placed over this rod g' , and confined thereon by a nut, g^7 , and by adjusting this nut the pressure by which the leveling-roller is borne or kept down upon the sole 85 during the reciprocations of the carrier is made more or less. This carriage is provided with forward and backward stops 89, so located 90 thereon as to operate upon an arm, c^5 , connected with the rock-shaft H, and operate it to disengage the hub from the pulley then driving it. These stops will be so located on 95 the carriage as to stop the machine should it be about to be moved too far by the carelessness of the operator.

It will also be noticed that the leveling-roller is supported at the front end of the carrier, that the carrier is unobstructed by any 100 connection with the machine at its front end, and as each shoe is leveled the carriage is moved backward far enough to remove the leveling-roller from the sole and the carrier and all parts of the apparatus from above the sole, 105 leaving it free to be treated in any way or the shoe to be removed.

I claim—

1. In a sole-leveling machine, a last to hold 110 a boot or shoe, an arm and carrier and leveling-roller swiveled thereon, combined with clutching mechanism under the control of the operator, to enable the leveling-roller to be moved over the sole for varying distances, as 115 may be desired, in one or the other direction, substantially as described.

2. In a sole-leveling machine, a last, a carriage, an arm pivoted thereon, and a swiveling carrier provided with a leveling-roller, and means, substantially as described, to reciprocate the said carriage and leveling-roller for a greater or less distance, as described, at the will of the operator, combined with a spring and connecting-link and treadle to hold the leveling-roller upon the surface of the sole at 125 substantially a uniform pressure, as and for the purpose set forth.

3. In a sole-leveling machine, the carriage-arm, swiveling carrier, and leveling-roller, and means to reciprocate the said carriage to 130

cause the roller to travel over the sole on the last, combined with a controller connected with the said arm, to limit the descent of the leveling-roller when passed off the toe of the last, as and for the purpose described.

5. In a sole-leveling machine, a reciprocating swiveling carrier and leveling-roller held therein, combined with a rotating spider containing two or more lasts, and with a locking

device for the spider, substantially as described.

In testimony whereof I have signed my name to this specification in the presence of two subscribing witnesses.

OTHNIEL GILMORE.
